UNITED STATES PATENT OFFICE.

PHILIP LINDEMEYR, OF BALTIMORE, MARYLAND.

VESSEL-TOP.

SPECIFICATION forming part of Letters Patent No. 763,618, dated June 28, 1904.

Application filed March 10, 1904. Serial No. 197,444. (No model.)

To all whom it may concern:

Be it known that I, PHILIP LINDEMEYR, a resident of Baltimore, in the State of Maryland, have invented certain new and useful 5 Improvements in Vessel-Tops; and I do hereby declare the following to be a full, clear, and exact description of the invention, such as will enable others skilled in the art to which it pertains to make and use the same.

10 The invention relates to vessel-tops or nozzles adapted for sprinkling or discharging the vessel contents in a small quantity at a time, and is an improvement on Patent No. 742,201 granted me October 27, 1903. The top of the 15 patented vessel cannot be closed after it is filled with the ink or the like without great care to avoid smearing the tools required for the operation.

The object of the present improvement is 20 to avoid this difficulty and to provide a sprinkling-top of the same general character that shall be applicable to vessels made of any material and to secure other obvious advantages.

The invention consists in the construction 25 hereinafter described and pointed out.

In the accompanying drawings, Figure 1 is a partial longitudinal section of the improved vessel, and Fig. 2 shows an enlarged vertical central section of the filling-nozzle and the 30 discharge-nozzle separate from the can. Fig. 3 is a partial plan view of a modified nozzle 4, and Fig. 4 is a sectional view on line 4-4 of Fig. 3.

Numeral 1 denotes the body of a can or other 35 vessel, which may be made of any suitable material and any desired size.

2 denotes a filling-nozzle made, preferably, of a comparatively large size for the convenient and cleanly introduction of liquids or semi-40 liquids. This nozzle may be provided with a bead 3 to facilitate securing thereto a reducing discharge-nozzle 4 of cup form. Said latter nozzle is made of a size circumferentially to fit the interior of nozzle 2 and preferably to exclude 45 the entrance of the vessel contents between them and of such length that its perforated bottom is in or near the plane of the top of the vessel-body.

The bottom of the nozzle 4 is provided with 50 a small discharge-opening 6, surrounded by an upwardly-extending bur or edge 7, adapted to penetrate a cork pressed down upon it.

The upper end of nozzle 4 has an outwardly and downwardly turned rim 8 engaging the bead 3, which rim may be corrugated more or less, as indicated in Figs. 3 and 4, to facilitate turning it around the bead. 55

9 denotes a packing of any suitable material to effectually seal the joint between the nozzles, the vessel being designed in some 60 cases for the use of materials having a highly volatile ingredient.

In manufacture the rim 8 is partially formed, the packing then inserted and the packed nozzle 4 pushed into nozzle 2, and the 65 rim 8 turned under against the lower side of bead 3. The nozzle 4 can be removed by opening out or spreading the rim 8 by the use of a suitable tool.

10 denotes a cork having a wooden cap 11; 70 but any suitable stopper may be employed, but preferably of such material that the flange or edge 7 may be made to penetrate it, as indicated.

Having thus described my invention, what 75 I claim as new, and desire to secure by Letters Patent, is—

1. The vessel having a comparatively large opening in one end, a nozzle fixed in said opening, and a cup-nozzle having a small discharge-opening in its bottom and joined to the nozzle first named, said joint comprising a rim of one 80 nozzle turned over upon the edge of the other, and a packing under the rim, said discharge-opening being surrounded by a flange to penetrate 85 a cork.

2. The vessel having a comparatively large opening in one end, a nozzle fixed in said opening, and a cup-nozzle having a small discharge-opening in its bottom and joined to the nozzle 90 first named, said joint comprising a rim of one nozzle turned over upon the edge of the other, said bottom being in substantially the same plane as the top of the vessel-body.

In testimony whereof I have signed this 95 specification in the presence of two subscribing witnesses.

PHILIP LINDEMEYR.
